Daniel Clow

UNITED STATES PATENT OFFICE.

DANIEL CLOW, OF JANESVILLE, WISCONSIN.

IMPROVEMENT IN HARVESTERS.

Specification forming part of Letters Patent No. 35,923, dated July 22, 1862.

To all whom it may concern:

Be it known that I, DANIEL CLOW, of Janesville, Rock County, and State of Wisconsin, have invented a new and Improved Harvesting Machine, or a new and useful improvement on the harvesting-machine; and I do hereby declare that the following is a full and exact description thereof, reference being had to the accompanying drawings, and to the letters of reference marked thereon.

Figure 1 represents an elevation; Fig. 2, a top view; Fig. 3, a plan or top view of parts detached from the frame; Fig. 4, a side view of the cross-head C; Fig. 5, a bottom view of same; Fig. 6, a vertical section through the stirrup and pitman.

The letters represent the different parts of said machine.

L M N is the main supporting-frame, which is constructed in the common way. A is the main driving-wheel, K the shaft, and F F² the arms of same. B is a cam attached to the inner periphery of the driving-wheel. C is a cross-head. D is a pitman. a is a key. E is a stirrup. G G² are springs. H is a hub or fulcrum. J J² are bolts and nuts. I I² are cams upon the under side of the cross-head C, as in Figs. 4 and 5. P is a nut. q is a washer. R is a bolt. s is a recess in the edge of the pitman D. o is a hole in the end of the said pitman, where the sickle-bar is attached.

Having named the several parts of the said machine, I will now explain its operation and construction as best I can.

The frame L M N of the said machine is made in the usual way, the driving-wheel A also, with the exception that the arms F F² thereof are attached to the side of the rim. Upon the inner periphery of the said wheel I place a zigzag way or cam, B, sometimes whole and at other times in sections. I prefer the sections, for the reason that it is more easily repaired. In front of the said wheel and between the cross-beams L L, I place the stirrup E, and fasten it to the said beams with the bolts and nuts j j²; and it is obvious that the said stirrup can easily be tilted toward the rear of the said machine, or toward the front, as may be required, which will be more fully explained hereinafter. Now, this said stirrup is peculiarly constructed with a base and sides or ears. At right angles with the same, upon the upper surface of the said base, is a hub or

fulcrum, H, and the pitman D hangs upon this said hub, the hole through the said pitman corresponding in size with the said hub, and the height of the said hub corresponds also with the thickness of the said pitman. Now, I insert a bolt, R, through the center of the said hub from the bottom of the said stirrup. Now, when the said pitman is in its proper place, as described, and as seen in Fig. 6, I place a washer, q, upon the top of the said hub, (the said bolt passing through the center of it also,) and then I put the nut p upon the said bolt and screw it down upon the top of the said washer, which said washer lies upon the top of the said hub, and in this way permanently secure the said pitman in its place; but it will be understood that the said pitman is sufficiently relieved to admit of free action.

It will be seen in Fig. 2 that the fulcrum of the said pitman is immediately in front of the said driving-wheel; hence the necessity of crooking the rear end to pass by the side of the said wheel. Upon the rear end of this said pitman I place the cross-head C, and fasten it there with the key a, as seen in Fig. 3, a mortise being in the end of the said cross-head, corresponding in size with the size of the end of the said pitman. On the inner edge of the said pitman is a recess or boxing, s, into which the said cross-head is placed, and is permanently held there when the said key is inserted into its proper place, as seen in Fig. 3. The said cross-head is constructed with cams I I² on the under side thereof, as seen in Figs. 4 and 5, corresponding with the angle of the said cam upon the inner periphery of the driving-wheel. It is manifest, therefore, that when the said cross-head is properly adjusted to the said cam on the said wheel and the said wheel set in motion the said cross-head, and consequently said pitman, will vibrate equally with the angles or radius of the said cam. The said pitman being pivoted at or near the middle thereof it is also manifest that the other or front end thereof will also vibrate in the same proportion with the rear end. The sickle or cutting apparatus, being attached to the front end of the said pitman at the point O, as seen in Fig. 3, is also set in motion when the machine moves.

The springs G G² are attached to the sides or ears of the said stirrup E, and extend for-

ward in the plane of the said pitman, sufficiently inclined toward the same to bring them in contact with the sides thereof at or near the end. The use of the said springs is to soften the action of the said cross-head upon the said cam and to regulate the motion of the entire machine. The object of hinging the said stirrup upon the said bolts j j^2 , (as before stated,) is to enable me to throw the machine in and out of gear, for it is clearly manifest that when I tilt it toward the front the rear end of the said pitman will raise and consequently detach the said cross-head from the said cam of the said wheel, and therefore stop, the motion of the said cutting apparatus; and when I reverse the position of the said stirrup by tilting it toward the rear of the said machine it brings the said cross-head in contact with the said cam again, and thereby sets the cutting again in motion, and vice versa.

What I claim, and desire to secure by Letters Patent, is—

1. The adjustable hinged stirrup E, in combination with the pitman D, when constructed and arranged in relation to each other as specified, and for the purposes described.
2. The springs G G^2 , in combination with the said stirrup E and the pitman D, when the several parts are constructed, arranged, and operate in the manner and for the purposes specified.
3. The cross-head C, in combination with the said pitman and the main driving-wheel A, when the several parts are constructed, arranged, and operate in the manner and for the purposes specified.

DANIEL CLOW.
